CENTERLINE GAUGE

Charles J. Fortriede, Redondo Beach, Calif.
(4322 Ocean Drive, Manhattan Beach, Calif. 90266)

Continuation-in-part of abandoned design application Ser.
No. 21,068, Jan. 26, 1970. This application Jan. 28,
1971, Ser. No. 110,798

Term of patent 14 years

Int. Cl. D10—04

U.S. Cl. D52—6 B

Fig. 1.

Fig. 2

FIG. 1 is a front perspective view of a centerline gauge showing my new design; and

FIG. 2 is a rear perspective view thereof.

This application is a continuation-in-part of design application Ser. No. 21,068, filed Jan. 26, 1970, and now abandoned.

I claim:

The ornamental design for a centerline gauge, substantially as shown.
